United States Patent Office

Des. 210,451
Patented Mar. 12, 1968

210,451

SKI POD

Vincent E. Gardner, Wayne, Mich., assignor to Marilyn
Sue Powers, Allen Park, Mich.

Filed Apr. 12, 1967, Ser. No. 6,653

Term of patent 14 years

(Cl. D14—27)

FIG.1

FIG.2

FIG.3

FIG.4

FIG.5

FIGURE 1 is a perspective view of a ski pod showing the new design.

FIGURE 2 is a top view of the new design.

FIGURE 3 is a side elevation view of the new design.

FIGURE 4 is a partial end elevation view showing the new design with the pod opened.

FIGURE 5 is a transverse section view of the new design taken substantially on the line 5—5 in FIGURE 2.

FIGURE 6 is a longitudinal section view of the new design taken substantially on the line 6—6 in FIGURE 2.

The fragmentary disclosure of an automobile in FIGURE 3 and of skis in FIGURE 5 is included only for illustrative purposes.

I claim:

The ornamental design for a ski pod, substantially as shown and described.
